(57) **CLAIM**

The ornamental design for a rechargeable LED stick light, as shown and described.

DESCRIPTION

FIG. 1 is a perspective view of the rechargeable LED stick light showing our new design;

FIG. 2 is top plan view;

FIG. 3 is a bottom plan view;

FIG. 4 is a side elevation view of FIG. 1;

FIG. 5 is an opposite side elevation view of FIG. 1;

FIG. 6 is a front elevation view of FIG. 1; and,

FIG. 7 is a rear elevation view of FIG. 1.

The broken line showing of the rechargeable LED stick light is for the purpose of illustrating portions of the article and forms no part of the claimed design.

1 Claim, 3 Drawing Sheets
